The present invention relates to containers and, more particularly, to the formation and construction of an improved container of the type having an end member formed of a plurality of laminations of fibrous material. In its principal aspects, the invention is concerned with an improved end connection between the body and end walls of a fibrous shipping container, and to methods of manufacture thereof.

During recent years there has been a persistent and ever increasing demand for practical and reliable shipping containers which are made of fiber, paperboard, or other suitable natural or synthetic non-metallic fibrous materials, yet which are capable of withstanding deformation forces during periods of storage, transportation, and use. As a consequence, it has been a common practice in the container industry to manufacture non-metallic shipping containers having an end member or closure comprising a disc formed of fiber, plywood, or similar material, with the disc being attached to the container body wall by means of a pair of axially spaced, inwardly extending, circumferential ribs formed in the body wall in confining relation to the peripheral edge of the end member. On occasion, the container end member has comprised a laminated fibrous disc in which the different laminations have identical diameters substantially equal to the internal diameter of the body wall, thus permitting the end member to "seat" on one of the ribs or "shelves" formed in the body wall and to be held in place thereon by the other of the body ribs. Of course, in these types of container constructions, the end member does not contribute in any way to the strength of the connection between the end member and the body wall. Indeed, such containers are characterized by their inherent weakness at the junction of the end and body walls and the consequent tendency of the end wall to pull or snap out of the confining ribs when the container is heavily loaded or when the container is dropped or otherwise subjected to deformation forces during transportation, storage and handling. When this occurs, often all or a substantial portion of the container contents are either lost or contaminated. Moreover, even in the undamaged state, the connection often does not meet the requisite conditions of "tightness" demanded by the users of such containers so as to insure that the latter are substantially substance-tight.

Yet another approach to the problem that has heretofore been taken by the manufacturers of fibrous shipping containers have involved the use of an end member or closure formed of a plurality of discs having unequal diameters. In this type of construction, the main disc, that is, the disc which contributes most to the thickness of the end member, is normally the disc having the smallest diameter with the particular diameter selected being equal to or slightly less than the internal diameter of the body wall. The remaining disc or discs have a greater diam-

2

eter than either the main disc or the body wall, and the peripheral overhanging edges of the larger disc or discs are then folded over and embedded in a curled or folded seam-like connection with the body wall. While this type of container construction is somewhat stronger and tighter than the first mentioned prior art construction, it has still not provided a satisfactory solution to the problem. Thus, when containers embodying this latter type of construction are subjected to rough handling, the end member still tends to pull out of the seamed connection since it is held in place by only the relatively weak peripheral edges of the layers having the larger diameters.

Yet another disadvantage of this latter type of conventional container construction resides in the fact that the container end member must be fabricated from pre-blanked discs having unequal diameters, such discs subsequently being secured together by a suitable adhesive.

It is a general aim of the present invention to provide an improved container construction, and method of manufacture thereof, which overcomes all of the foregoing disadvantages and which is characterized by its ease of manufacture.

More specifically, it is an object of the invention to provide a laminated or multiple layer fibrous end member for shipping containers which permits of an improved seamed connection between the body and end members, which connection is characterized by its strength, tightness, and resistance to deformation forces of the type normally encountered in handling, transportation and storage. While not so limited in its application, the invention will find especially advantageous use in connection with shipping containers of the type which not only employ laminated fibrous end members, but which also employ laminar fibrous body walls made, for example, by conventionally or helically winding a web of fibrous sheet material about a forming mandrel or the like.

A further object of the invention is the provision of an improved seamed connection between the body and laminated, fibrous end walls of a shipping container which permits of the use of relatively inexpensive and weak fibrous material in the central layer of a multiple layer or "sandwich" type container closure, yet which is nevertheless characterized by its strength and reliability in use. As a consequence of attaining this objective, containers embodying the present invention may be made at lower cost by economizing in material quality, material costs, and labor, while at the same time the resultant container will be stronger than those heretofore known in the prior art.

In another of its important aspects, it is an object of the invention to provide an improved container end connection employing at least three laminations of fibrous sheet material, and to improved methods of manufacture thereof, wherein the relatively weak central fibrous lamination is maintained substantially free of tensile forces during both the seaming operation and in the field when, for example, a heavily loaded container is subjected to shocks or vibrations, and wherein substantially all of the stress is absorbed by the relatively strong outer layers or laminations.

An ancillary object of the invention is the provision of a novel reinforced end connection between the body and end walls of a fibrous shipping container and which permits use of a lighter gauge metallic reinforcing ring than is commonly employed with conventional reinforced con-

tainer constructions, yet wherein substantially the same degree of strength and protection is afforded the seamed connection by the lightweight metallic reinforcing ring as has heretofore been afforded the seamed connection of conventional containers employing heavier gauge metallic reinforcing rings.

Other objects and advantages of the invention will become apparent as the following description proceeds, taken in conjunction with the accompanying drawing, in which:

FIGURE 1 is a side elevation of a shipping container embodying the features of the present invention;

FIG. 2 is a vertical cross-sectional view on an enlarged scale taken substantially along the line 2-2 in FIG. 1, here depicting details of the improved connection between the body and end walls of the exemplary container;

FIG. 3 is a vertical cross-sectional view similar to FIG. 2, here illustrating the novel container end connection during an initial stage in the method of manufacture thereof; and,

FIG. 4 is an enlarged vertical cross-sectional view similar to a portion of FIG. 2, but here depicting a slightly modified end wall construction also embodying the features of the present invention.

While the invention is susceptible of various modifications and alternative forms, a specific embodiment thereof has been shown by way of example in the drawing and will herein be described in detail. It should be understood, however, that it is not intended to limit the invention to the particular form disclosed, but, on the contrary, the intention is to cover all modifications, equivalents and alternatives falling within the spirit and scope of the invention as expressed in the appended claims.

Referring more particularly to the drawing, there is illustrated in FIG. 1 an exemplary shipping container, generally indicated at 10, made in accordance with the present invention. As best illustrated in FIG. 2, the exemplary container 10 includes a body wall 11 and a closure or end member, generally indicated at 12, the wall 11 and end member 12 being seamed together as shown at 14. In this instance the end member 12 constitutes the container bottom. However, as the ensuing description proceeds, it will become apparent that a similar end member could also be secured to the upper end of the body wall 11 in accordance with the invention, thus providing a container top (not shown). In this latter event, it would simply be necessary to provide suitable means for filling the container and for subsequently discharging the contents thereof such, for example, as the provision of a filling and discharging orifice or, alternatively, by making the body wall 11 of two separable portions.

In the illustrative container 10, the end member 12 is of a "sandwich-type" construction, consisting of an inner central layer or lamination 15 sandwiched between a pair of outer layers or laminations 16. The individual laminations may be made of a wide variety of commercially available fibrous sheet materials such, for example, as fiber, paper, or other natural or synthetic materials. However, in order to facilitate the ensuing description, the invention will be described in conjunction with a cylindrical container 10 having an end member 12 consisting of an inner or central layer 15 of relatively weak and inexpensive paperboard such, for example, as millboard or chipboard, the central layer being sandwiched between a pair of relatively strong fibrous outer layers 16 which, merely by way of example, may comprise sheets of kraft liner board. Similarly, the body wall 11 of the container may also be formed of suitable fibrous materials. For example, the body wall may be of laminar construction (not shown) and formed of a web of kraft paper or the like wound convolutely or helically about a suitable forming mandrel. Moreover, the body wall may, if desired, have other than the cylindrical configuration shown.

In accordance with one of the important aspects of the present invention, provision is made for seaming the end

member 12 to the body wall 11 in such a manner as to form a seamed end connection 14 characterized by its strength and tightness and wherein the tendency of the end member 12 to pull out of the seamed connection is substantially eliminated. To accomplish this, the end member 12 is formed of a plurality of equidimensional laminations 15, 16 as measured in a transverse direction; e.g., where the container is cylindrical as here shown, the layers 15, 16 have equal or substantially equal diameters and, the initial diameter of all layers exceeds the internal diameter of the container wall. As a consequence of this construction, when the peripheral edge of the end member 12 is folded over with the marginal extremity of the body wall by means well known to those skilled in the art, all of the layers or laminations which make up the end member are folded into the seamed connection 14.

In the illustrative form of the invention, the body wall 11 of the container 10 has formed therein an inwardly extending circumferential rib 18 which is formed adjacent the marginal extremity of the body wall. Thus, when the end member 12 and body wall 11 are seamed together, an annular portion of the end member is securely clasped or clamped between the seamed connection 14 and the rib 18, thus enhancing the strength of the connection.

In order to further enhance the strength of the connection 14 and to increase its resistance to deformation forces, a metallic reinforcing ring 19 may be positioned in proximity to the connection prior to the seaming operation, for example, by placing the ring 19 in surrounding relation to the marginal extremity of the body wall 11. Thus, when the body wall 11 and end member 12 are seamed together, the reinforcing ring 19 is folded over with the body wall and end member with the free extremity of the ring 19 being clamped in the seamed connection. Of course, the ring 19 could be secured to the container in other ways and still serve to reinforce the resultant improved connection. For example, the ring 19 could be mounted within the fold seam 14 and its edge similarly folded over together with the peripheral edge of the end member 12 and the marginal extremity of the body wall 11.

In keeping with the preferred form of the invention, the end member 12 comprises at least three layers of fibrous material. The central layer 15, which provides the body of the end member, is formed of paperboard or the like, and it serves to space the relatively stronger outer layers 16 apart, thus providing additional strength. Since the central layer 15 is sandwiched between relatively stronger outer layers 16, the latter preferably being made of kraft liner board or the like, the central layer can be made of fibrous material of relatively poorer quality such as millboard or chipboard. Although the poorer quality millboard or chipboard is normally not capable of withstanding the deformation resulting from the seaming operation, the protection afforded by the stronger outer layers 16 prevents cracking or breaking of the central layer as the latter is folded. In actuality, deformation of the laminated end member 12 during the seaming operation causes, at most, delamination of the central layer into several layers which slide over one another but which each remain intact and do not break. As a consequence, a great number of unbroken layers separated from one another by delamination are embedded in the seamed connection 14, thus substantially enhancing the strength of the latter. It has been found that when containers made in accordance with the invention are subjected to deformation forces, for example, forces resulting from prescribed "droptest" techniques well known to those skilled in the art, the end members 12 do not pull out of the seamed connection 14 and the latter remains tight.

In carrying out the invention, provision may also be made for improving the wear resistance of the end member 12. To this end, the outermost or external layer 16 (e.g., the lowermost layer 16 as viewed in FIG. 4) may be coated or impregnated with a bituminous liner 17.

While such a liner is water repellent, it does not afford a "moisture barrier" and, consequently, in keeping with this aspect of the invention, the bituminous liner may be laminated to the layer 16 by means of a layer 17' of bitumen.

To facilitate assembly of the body wall 11 and end member 12, the latter is initially formed with an upstanding peripheral flange 20 (FIG. 3), for example, by bending the edge of the laminar end member out of the plane of the central disc portion thereof. Thus, it is merely necessary to insert the end member 12 into the opening defined by the body wall 11 until it seats against the rib 18 with the flange 20 engaging the inner surface of the body wall. The flange 20 and body wall 11 are then seamed together.

In accordance with another of the important aspects of the present invention, provision is made for controlling the internal stresses developed in the end member 12 during a seaming or folding operation. To this end, at least the outermost layers 16 of the end member 12 are put under radial tension during the seaming operation. To accomplish this, the peripheral flange 20 is preferably formed with a slight taper (as best shown in FIG. 3) so that the flange 20 flares outwardly from the end member 12. The degree of taper is such that the maximum diameter of the tapered flange is substantially equal to the internal diameter of the body wall 11 while the smallest diameter of the tapered flange is considerably less than the internal diameter of the body wall 11. Thus, during a seaming operation the end member 12 is effectively placed under a radial tension. As the seaming operation progresses, the free extremity of the body wall 11 is compressed or contracted, thereby tending to expand the latter so as to increase, or at the very least, to maintain the tension in the outer layers 16 of the end member 12 upon removal of the container 10 from the seaming apparatus.

It will be appreciated from the foregoing description, that the present invention also contemplates novel methods for forming containers of the type having laminar fibrous end walls joined to the container body wall. Thus, in manufacturing containers 10 in accordance with the invention, a peripherally continuous body wall 11 is formed, the wall preferably having a circumferential, inwardly extending rib 18 formed therein. In those instances where the body wall 11 is also of laminar fibrous construction, the wall may be formed in a conventional manner as, for example, by convolutely or helically winding a web of sheet material about a forming mandrel. A laminated end member is then formed by sandwiching a sheet of paperboard or the like between axially spaced layers of relatively stronger fibrous material such as kraft liner board. The individual laminations or layers have like transverse dimensions and all are initially formed slightly larger than the internal dimension of the body wall 11. The peripheral edge of the end member 12 is bent to form an upstanding flange either prior to or incident to insertion of the end member into the opening in the body wall 11, and the flange thus formed is then folded over with the marginal extremity of the body wall 11 to form a novel seamed connection 14. The rib 18 formed in the body wall 11 serves as a seat for the end member 12, thus insuring that when the two pieces are seamed together, an annular portion of the latter is clamped between the rib and the seamed connection. Still greater strength is achieved by positioning a metallic reinforcing ring in proximity to the seamed connection prior to a seaming operation and simultaneously folding the ring, body wall extremity, and peripheral edge of the end member together to form a reinforced seam.

In forming containers in accordance with the preferred method of the invention, the end member 12 is placed under radial tension during the seaming operation, that is, the outer layers 16 are subjected to radial tensile forces during the seaming operation and, since seaming causes

the body wall to tend to expand in the vicinity of the plane of the end member, such radial tension is maintained even after the container is removed from the seaming apparatus. It has been found that this serves to increase

5 the resistance of the end member 12 to bending loads, shock, blows, and vibrations. Thus, the outer layers 16 of the end member act as a membrane or diaphragm clamped tight about its periphery, and substantially all of the stresses incurred are taken up by the relatively

10 strong outer layers 16.

It will be observed that since the present invention contemplates laminar end members 12 having equal diameters, the different layers may be glued or otherwise bonded together in laminar form while in the sheet or web

15 state, thus permitting completely formed end members to be blanked directly from the sheet or web thus formed. This, of course, insures substantial savings in both time and expense over the prior art constructions wherein the various layers had different diameters, thus requiring 20 that each lamination be preblanked prior to its assembly with adjacent laminations.

Of course, those skilled in the art will appreciate that the outer layers 16 of the container bottom may possess other characteristics in addition to being stronger than the

25 central layer 15. For example, one or both of the layers 16 may be formed of a liquid impervious material. Alternatively, the outermost layer 16 (i.e., the bottom layer as viewed in FIG. 2) may have liquid repellent properties while the internal layer 16 (i.e., the top layer as viewed

30 in FIG. 2) may be liquid impervious.

It has been found that containers embodying the features of the present invention are characterized by their strength and durability, particularly in the region of the seamed connection 14. Moreover, in those instances 35 where the container requires additional protection in the form of a reinforcing ring 19, the latter can be formed of a lighter gauge metal than is conventionally used while still attaining the same degree of additional reinforcement.

40 We claim as our invention:

1. A shipping container comprising, in combination, a body wall, an end wall, said end wall being formed of at least three laminations of sheet material with said laminations being substantially equidimensional transversely 45 thereof and having an initial diameter greater than the internal diameter of the body wall, the outermost ones of said laminations being formed of relatively strong fibrous material sandwiching the central lamination, said central lamination being formed of fibrous material relatively weaker than the fibrous material defining said outermost laminations, the peripheral edges of all of said laminations being bent out of the plane of said end wall to define a laminated peripheral flange surrounding a central disc portion of said end wall, and said flange and 55 the marginal extremity of said body wall being folded together inwardly beneath said central disc portion to define a fold seam connection therebetween rigidly securing said end wall to said body wall.

2. A shipping container as set forth in claim 1 further characterized in that said outermost laminations are formed of kraft liner board and said central lamination is formed of paperboard.

3. A shipping container as set forth in claim 2 further characterized in that said central lamination is formed of millboard.

4. A shipping container as set forth in claim 2 further characterized in that said central lamination is formed of chipboard.

5. A shipping container as set forth in claim 1 further characterized in that the external one of said outermost laminations is coated with a layer of bituminous liner material.

6. A shipping container as set forth in claim 5 further characterized in that said layer of bituminous liner ma-

terial is laminated to the adjacent lamination by means of a layer of bitumen.
